New York, Sept. 19th 1863.

Thos. G. Harold

Samuel W. Gorrell

B. R. Crooker

UNITED STATES PATENT OFFICE.

THOMAS GEORGE HAROLD, OF BROOKLYN, NEW YORK, ASSIGNEE TO
HIMSELF AND JOHN W. KISSAM, OF SAME PLACE.

IMPROVEMENT IN LOCKS.

Specification forming part of Letters Patent No. 40,724, dated November 24, 1863.

To all whom it may concern:

Be it known that I, THOMAS GEORGE HAROLD, of Brooklyn, in the county of Kings and State of New York, have invented, made, and applied to use a certain new and useful Improvement in Locks; and I do hereby declare the following to be a full, clear, and exact description of the said invention, reference being had to the annexed drawings, making part of this specification, wherein—

Figure 1 is an exterior view of my lock. Fig. 2 represents the same as with one side of the case removed. Fig. 3 is a vertical section transversely of the lock. Fig. 4 is the key; and Fig. 5 is a modification of my improvement, showing the same as applied to a lock for draws, doors, &c.

Similar marks of reference denote the same parts.

Locks have heretofore been made with sectional stop-pins acted on by springs, and in which a corrugated key brings all the pins into such a position that the divisions between the parts of the pins are in line with the parts of the lock to be turned on each other.

The nature of my said invention consists in a lock-case of two parts fitted to screw or lock together and prevented from turning by the bolt or hasp, in combination with stationary and turning blocks containing divided stop-pins, whereby the position of said pins can be changed to effect a permutation of the lock by opening the case when unlocked. I also make use of a curved hook-bolt extending from the turning block to the curved interior of the lock-case, whereby said hook-bolt is sustained by said case, and strain from the hasp or bolt on said hook is not taken on the divided stop-pins; thereby the lock is rendered less liable to be picked, because the turning block cannot be strained sidewise by pulling on the hasp or bolt.

In the drawings, *a* and *b* are the shells of the lock, which are screwed together, as at *c*, or secured by sectional inclined or screw-formed lugs within the case; and *d* is the shackle or bolt, hinged at *e*, and entering mortises in the parts *c* of the case, so that the case cannot be unscrewed or taken apart when the lock is locked, the same as shown in my patent of August 5, 1862.

Secured upon or formed with the case *a* is a

block, *f*, that is formed circular around its flat end and receives the rear flat circular face of the moving block *g*. At *i* the block *g* is formed with a circular flange surrounding the block *f*, so that the block *g* can be turned upon *f*, but will be held in position with the same by this flange *i*. It will be seen that for this purpose the circular flange *i* might be on the block *f* and a circular recess in *g*.

h h are divided stop-pins in *f* and *g*, kept forward by the springs *k*; and *l l* are holes at the ends of the pins *h h*, that are smaller in size than such pins, so that the springs *k* cannot eject the stop pins *h*, but at the same time the pins *m m* of the key *n* can pass through such holes and act upon the stop-pins. The divisions between the back and front portions of the stop-pins *h* are at such points that when the key-pins *m* are pressed against the ends of the pins *h* said divisions are at the point where *f* and *g* come together, and hence the block *g* can be rotated for unlocking the lock, but when the lock is locked the rear portions of the divided stop-pins project into the holes in *g*, and said block *g* cannot be turned; hence the lock cannot be opened until the correct key is applied to press each stop pin back its own proper distance. Upon this block *g*, or actuated by it, is the bolt or hook *o*; that in Figs. 2 and 3 is shown of a character to enter a mortise in the shackle *d* and retain the same, while in Fig. 5 this bolt *o* is shown as projecting beyond the lock-shell *a'* in a manner that would be required for a door-lock or a lock for draws, boxes, &c.

p p are stops to determine the amount of motion allowed to the block *g* and hook *o*, Fig. 2. The shell *b* when screwed on retains the block *g* in its place by the shoulder, as seen in Fig. 3, but at the same time the block *g* can be turned by the key *n*. I provide a groove, *r*, across the front face of the block *g*, which facilitates the entrance of the pins *m* of the key into their respective holes, and at the same time receives the flat plate forming the key, so that the pins are relieved in turning said block. When the case *a b* is together, the hook or bolt *o*, Fig. 2, moves contiguous to the inside of the case *b*, and hence is supported by said case when through the mortise in the hasp.

It will be evident that this lock can easily

be taken apart and the divided stop-pins changed into different holes, so that the lock is adapted to a key with the lengths of pins differently placed, so that a lock can be made secure at the expense of a new key in case of the former key being lost or stolen.

Having thus described my said improvements, what I claim, and desire to secure by Letters Patent, is—

1. A lock-case of two parts, fitted to screw or lock together and prevented from turning by the bolt or shackle, as specified, in combination with the stationary and turning blocks and divided stop-pins, whereby opportunity is afforded for changing the position of the said

stop-pins and adapting them for a different key, as set forth.

2. The hook-shaped bolt extending from the turning block and contiguous to and supported by the curved interior of the lock-case, in combination with the divided stop-pins and with the hasp or bolt, whereby the strain on the hasp or bolt is taken by the lock-case instead of the divided pins, as specified.

In witness whereof I have hereunto set my signature this 19th day of September, 1863.

THOS. GEO. HAROLD.

Witnesses:

LEMUEL W. SERRELL,

S. R. CROOKER.
